(57) **CLAIM**

The ornamental design for a liquid and cup dispenser, as shown and described.

DESCRIPTION

FIG. 1 is a top perspective view of my new design for a liquid and cup dispenser;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof;

FIG. 8 is an exploded view thereof;

FIG. 9 is another top perspective view thereof, shown in a configuration of use;

FIG. 10 is a top perspective view of the my new design for a liquid and cup dispenser, shown with the bottom cover removed for clarity of disclosure;

FIG. 11 is another top perspective view of FIG. 10, shown in a configuration of use;

FIG. 12 is a back view of FIG. 10;

FIG. 13 is a first side view of FIG. 10;

FIG. 14 is a second side view of FIG. 10;

FIG. 15 is a top view of FIG. 10;

FIG. 16 is a bottom view of FIG. 10; and,

FIG. 17 is a rear perspective view of a golf cart showing the dispenser installed in place and ready for use.

The portions of the liquid and cup dispenser shown in broken lines form no part of the claimed design.

The broken line showing of a golf cart in FIGS. 9 and 17 depicts environmental subject matter and forms no part of the claimed design.
